(57) **CLAIM**

Related U.S. Application Data

(63) Continuation-in-part of application No. 29/277,192, filed on Feb. 16, 2007, now Pat. No. Des. 568,748.

The ornamental design for a portion of a bottle, as shown and described.

(51) **LOC (9) Cl.** **09-01**

DESCRIPTION

(52) **U.S. Cl.** **D9/516**

FIG. 1 is a perspective view of a portion of a bottle showing our new design;

(58) **Field of Classification Search** **D9/516,**

FIG. 2 is a front view thereof;

D9/518, 523, 526, 529, 530, 549, 550, 551,

FIG. 3 is a left side view thereof;

D9/552, 558, 562, 571, 574, 575; 215/381-385

FIG. 4 is a top view thereof;

See application file for complete search history.

FIG. 5 is a rear view thereof;

FIG. 6 is a bottom view thereof; and,

FIG. 7 is a right side view thereof.

(56) **References Cited**

The broken lines showing the top and bottom portions of a bottle appearing in FIGS. 1-7 define the bounds of the claimed design and/or disclose the environment related to the claimed design, and therefore form no part of the claimed design. Applicants reserve the right to amend this application and/or to file one or more divisional or continuation applications to specifically claim or disclaim any of the elements in the drawings.
